UNITED STATES PATENT OFFICE.

JAMES B. KIRBY, OF CLEVELAND, OHIO.

DESIGN FOR A CASING FOR PNEUMATIC CLEANERS.

43,147.

Specification for Design.

Patented Oct. 15, 1912.

Application filed July 29, 1911. Serial No. 641,229. Term of patent 7 years.

To all whom it may concern:

Be it known that I, JAMES B. KIRBY, a citizen of the United States of America, residing at Cleveland, in the county of Cuyahoga and State of Ohio, have invented a new, original, and ornamental Design for Casings for Pneumatic Cleaners, of which the following is a specification, reference being had to the accompanying drawings, forming part thereof.

Figure 1 is a front elevation of a casing for a pneumatic cleaner showing my new

design. Fig. 2 is a side elevation of the same.

I claim—

The ornamental design for a casing for a pneumatic cleaner, as shown.

In testimony whereof, I sign the foregoing specification, in the presence of two witnesses.

JAMES B. KIRBY.
